UNITED STATES PATENT OFFICE.

BYRON ALLEN, OF SOUTHBURY, CONNECTICUT.

DROP BOARD FOR DROP PRESSES.

Application filed March 31, 1922. Serial No. 548,551.

To all whom it may concern:

Be it known that I, BYRON ALLEN, a citizen of the United States, residing at Southbury, in the county of Hartford and State of Connecticut, have invented a new and useful Improvement in Drop Boards for Drop Presses; and I do hereby declare the following, when taken in connection with the accompanying drawings and the characters of reference marked thereon, to be a full, clear, and exact description of the same, and which said drawings constitute part of this application, and represent, in—

Fig. 1 a view in elevation of a simple form of drop-press.

Fig. 2 a broken perspective view of a discarded drop-board such as is used in practicing my invention, the composite drop-board units, into which it is to be cut, with their tongues and grooves, being indicated by broken lines.

Fig. 3 a broken perspective view showing two of the composite drop-board units.

Fig. 4 a broken perspective view, showing one of the finished composite drop-boards.

Heretofore it has been found, by long experience, that rock maple boards, cut from specimen trees grown in the open, are, on account of their particular physical characteristics, peculiarly adapted for use in drop-presses. Up to this time, no satisfactory substitute for boards cut from rock-maple trees grown in the open, has been found. The supply of such rock-maple boards from trees grown in the open is rapidly diminishing and hence each board is utilized to the limit before being discarded. Thus, the upper end-portion of the board, which is the portion thereof exposed to the gripping action of the lifting-rolls of the press, becomes, in use, so condensed that the lifting-rolls fail to grip and lift it. The board is then reversed, end for end, in the press, whereupon what was its lower or hammer-carrying end becomes its upper or gripping end. When this end of the board has been so condensed that the board fails to function, the board is utilized in the same way in a smaller press, and so on, until it has been so compressed that it is not available for use in the smallest drop-presses. The board is then discarded, notwithstanding the fact that on account of the condensation of its fibers in use, it is, when discarded, stronger and better adapted

for this particular use in a drop-press than when first put into use.

The object of my invention is to effect an economy in the use of such open-grown rock maple boards and to provide a drop-press board of superior character. With this end in view, my invention consists in a composite drop-board for drop-presses consisting of a plurality of pre-condensed units firmly bound together with their condensed faces in abutment.

For the illustration of my invention, I have shown a simple form of drop-press having a drop-board 5 provided at its lower end with a hammer 6 and having its upper end passed between two lifting-rolls 7 and 8, of which the latter is laterally movable toward and away from the board, by means of an eccentric bearing 9 operated by an arm 10 connected by a long link 11 with an operating-lever 12 having a hand-grip 13. When the lever 12 is depressed, the board 5 is pinched between the lifting-rolls 7 and 8, which grip it and lift it; then, after the board 5, and hence the hammer 6, have been lifted to the necessary height, the lever 12 is lifted for releasing the board, permitting it and the hammer to drop. In other forms of presses, one or both of the rolls are operated so as to automatically grip the board and release it. Drop-presses of the character described are so well known in the art as to need no further illustration or description.

On account of the severe compression of the boards required for pinching them sufficiently to secure the grip necessary for lifting the hammers, the boards are condensed and so much reduced in thickness that after a time the lifting-rolls fail to grip and lift them. Any given board, so condensed at one end, is reversed, end for end, and so used until its then upper end has been so condensed and thinned that it is no longer gripped by the rolls of the same press. The board is then shifted to a smaller drop-press, and so on, until it is so condensed throughout its length that it can no longer be used as a drop-press board. Heretofore, at this stage, the board has been discarded, although, at this time, on account of having been condensed, the board is actually stronger and better adapted for resisting the racking strains and jars of a drop-press than when it was first put in use.

My invention consists in longitudinally

slitting these discarded boards into strips, or, as I may say, composite drop-board units, and assembling the same with their condensed faces in abutment. Thus, the board shown by Fig. 2 is slit to form two intermediate-units 14 and end-unit 15, as shown more clearly in Figs. 3 and 4, the intermediate-units 14 being differentiated from the end-units 15 in having both of their outer or compressed faces formed with tongues and grooves 16 and 17, while the latter has only one face so tongued and grooved. Such units are secured together by glue or cement, as shown in Fig. 4. By preference, the upper and lower ends of the units are united by transverse bolts 18, as shown.

It will be understood, of course, that in the production of one of my improved composite drop-press boards, more than one discarded board will be required to produce a drop-board of the original dimensions of the discarded boards utilized in producing the new board, although, of course, a large discarded board might be utilized in making a single small board in accordance with my

invention. As a general thing, two discarded boards would be required for producing one of my improved boards. It will be observed that the abutting faces of the units of my improved board are the condensed faces of the original boards. 30

I am thus enabled, by means of my invention, not only to effect a great economy in re-using the material in discarded boards, but to produce superior boards, inasmuch as 35 the material in them has been pre-hardened by use.

I claim:

A composite drop-board for drop-presses, consisting of a plurality of pre-hardened 40 strips or units having their condensed or hardened faces abutted and secured together.

In testimony whereof, I have signed this specification in the presence of two subscribing witnesses.

BYRON ALLEN.
